(57) **CLAIM**

The ornamental design for a fishing device, as shown and described.

DESCRIPTION

FIG. 1 is a front perspective view;

FIG. 2 is an expanded view of FIG. 1;

FIG. 3 is a top view of FIG. 1;

FIG. 4 is a front view of FIG. 1;

FIG. 5 is a side view of FIG. 1;

FIG. 6 is a rear view of FIG. 1;

FIG. 7 is a bottom view of FIG. 1; and,

FIG. 8 is an opposite side view of FIG. 5.

The broken lines included in FIGS. 1-10 are for the purpose of illustrating environmental structure and form no part of the claimed design.
